UNITED STATES PATENT OFFICE.

JOHN C. KITTON, OF SAN FRANCISCO, CALIFORNIA, ASSIGNOR OF ONE-HALF TO C. C. HUTCHINSON, OF OAKLAND, CALIFORNIA.

PLATE-ICE MACHINE.

SPECIFICATION forming part of Letters Patent No. 643,269, dated February 13, 1900.

Application filed April 6, 1899. Serial No. 711,982. (No model.)

To all whom it may concern:

Be it known that I, JOHN C. KITTON, a citizen of the United States, residing in the city and county of San Francisco, State of California, have invented an Improvement in Plate-Ice Machines; and I hereby declare the following to be a full, clear, and exact description of the same.

My invention relates to an apparatus for the cooling of air which may afterward be used under any conditions where cooling or refrigeration is needed. It may be applied to refrigerating air in storage-chambers of any character. In my present illustrations I have shown it as applied to the manufacturing of what is known as "plate-ice"—that is, ice which is frozen upon the surfaces of plates which are refrigerated from the interior, so that the ice forms outwardly from the surfaces of the plates until it has become of sufficient thickness.

It comprises details of construction, which will be more fully explained by reference to the accompanying drawings, in which—

25 Figure 1 is a vertical section through my machine. Fig. 2 is a similar section at right angles to Fig. 1, taken through the lower part of the fresh-water tank.

In the freezing of ice upon the surfaces of 30 large plates, which are submerged in fresh water, the temperature of the plates is reduced from the interior in the usual well-known manner. The ice at first forms rapidly upon the surfaces of the plates; but as the thickness 35 of the ice increases, being a poor conductor, the rapidity of the formation of ice decreases until the time necessary to form the desired thickness of ice will amount to several days. It is well known that this class, known as 40 "plate-ice," is superior to any which is formed by the can or any other method; but the time and expense of making it have made it inferior from an economic point of view.

It is the object of this application of my invention to overcome the objections of slow freezing and to increase the rapidity with which the ice can be formed by so reducing the temperature of the water between the gradually-forming plates of ice as to increase 45 the rapidity of its formation by practically

freezing from the outside, as well as that adjacent to the freezing-plate.

A is a fresh-water tank having as many freezing-plates B within it as may be desired. These plates extend transversely across the 55 tank, reaching from the bottom up to the surface of the water, and the temperature of the plates is reduced in the usual or any suitable manner, as by passing ammonia or other vapor through pipes or passages within the 60 plates and allowing it to expand therein, by which operation the heat is rapidly extracted and the temperature of the plates reduced below the freezing-point of water. This, being a common method and well known, is not here 65 illustrated.

C is a brine-tank having within it the refrigerating-coils D, through which the refrigerant vapor is passed, so that the temperature of the brine within the tank is kept 70 reduced to the lowest possible or desired degree.

E is an air-circulating apparatus. In the present case it is represented in the form of a rotary pump or blower. From this air-forcing mechanism pipes F extend into the lower part of the brine-chamber C, and these pipes are formed with downwardly and outwardly discharging openings or nozzles F', through which the air is discharged in fine subdivisions and allowed to rise up through the brine by its buoyancy. As it thus rises the heat is rapidly extracted, and its temperature is reduced to as low a point as may be desired. The construction of this brine-chamber may 85 be of any usual or suitable form, with proper arrangements for circulating the refrigerant vapor through the coils D. From the upper part of this brine-chamber a pipe or pipes G extend to a point below the freezing-chamber A. From the pipe G branches H extend into the lower part of the fresh-water chamber and are controlled by cocks I, which enable the operator to regulate the flow of air into different parts of the chamber or close 90 off same. As here shown, these pipes extend entirely across the lower part of the chamber and have upturned ends or nozzles at sufficiently close intervals, so that the air which has been reduced to a low temperature in the 95 100

brine-chamber is delivered into the fresh-water chamber A. The air thus discharged into the water being at a very low temperature rapidly extracts the heat from the water 5 between the forming ice plates and reduces its temperature to so low a point that the additional ice forming upon the outer surface of the plates is rapidly increased, and the reduction in the rate of freezing which would 10 otherwise occur by reason of the low conducting power of the already-formed ice is counteracted. From the top of the tank return-pipes J will deliver the air into a main pipe K, which delivers the air again into the air-forcing mechanism E, so that the air which is 15 discharged from this mechanism into the brine-tank will already be at a very low temperature, and a considerable economy is effected by thus using this air over and over.

20 Experience has shown that no transfer of saline particles of vapor from the brine to the fresh-water tank occurs. The pipes J are also provided with controlling-cocks L, so that the circulation of the air through different 25 parts of the large tank may be accurately controlled and the rate at which the ice is formed therein can be equalized. In this manner I am enabled to so increase the rate of formation in this class of machine that ice 30 twelve or fourteen inches in thickness can be formed in a very greatly reduced time, because by this operation a freezing-surface is practically provided upon the outside of the ice plate in addition to that which is produced 35 from the plate itself.

It will be manifest that air thus refrigerated may be used equally well for other purposes as well as the manufacture of ice, the essence of my invention being the cooling 40 of the air and reducing it to any desired low temperature by passing it upwardly through a refrigerating liquid the temperature of which has been suitably reduced for the purpose.

45 Having thus described my invention, what I claim as new, and desire to secure by Letters Patent, is—

1. The combination of a tank adapted to

contain fresh water and having freezing-plates extending transversely across it, a brine-tank 50 having a coil through which is circulated a refrigerating fluid, a rotary blower or pump between the fresh-water and brine tanks, having a discharge-pipe entering the brine-tank and discharging downwardly therein whereby 55 the air is permitted to rise through the brine, an air-conducting pipe connecting the upper portion of the brine-tank with the lower portion of the water-tank and having independent branches discharging air into the latter 60 at points between adjacent freezing-plates, and a return-pipe having branches corresponding with the branches of the conducting-pipe and connecting the upper portion of the water-tank with the blower whereby 65 air passing the plates is returned to the blower for reuse in the brine-tank.

2. The combination of a brine-tank provided with means for circulating a refrigerating fluid therethrough, a fresh-water tank 70 having freezing-plates, and air forcing and circulating mechanism including a rotary blower having a pipe leading from its discharge and entering the lower portion of the brine-tank, said pipe having a plurality of 75 flaring nozzles fitted to its under side and discharging air in fine subdivisions into the lower portion of the brine, a pipe entering the upper end of the brine-tank and thence extending downwardly below and along the water- 80 tank, and having vertical branches entering the bottom of the water-tank at points between adjacent freezing-plates, and having controlling-valves, a return-pipe having depending branches entering the upper portion 85 of the water-tank at points between said plates and valves controlling said branches, said return-pipe connecting with the suction end of the blower whereby the spent air is returned to the brine-tank for reuse. 90

In witness whereof I have hereunto set my hand.

JOHN C. KITTON.
